(57) CLAIM

The ornamental design for a sprayer for sand and debris removal, as shown and described.

DESCRIPTION

This application relates to a Utility patent application Ser. No. 11/306,676, filed on even date herewith, in the name of Frederick G. Ingraham, the entire teachings of which are incorporated herein by reference.

The design of the sprayer of the present invention includes an essentially spherical shape to mimic a beach ball, and is used to remove sand or debris from a person, e.g., a child that has been playing at the beach.

FIG. 1 is a perspective view of an essentially spherically shaped sprayer in one embodiment of the present invention.

FIG. 2 is a front view of the essentially spherically shaped sprayer of the present invention.

FIG. 3 is a top view of the essentially spherically shaped sprayer of the present invention.

FIG. 4 is a bottom view of the essentially spherically shaped sprayer of the present invention.

FIG. 5 is a side view of the essentially spherically shaped sprayer of the present invention.

FIG. 6 is a back view of an essentially spherically shaped sprayer of the present invention.

FIG. 7 is another side view of the essentially spherically shaped sprayer of the present invention; and,

FIG. 8 is a front view of an essentially spherically shaped sprayer of an embodiment of the present invention that mimics a beach ball.

The broken line showing is included for the purpose of illustrating and forms no part of the claimed design.
